UNITED STATES PATENT OFFICE.

NELS T. NELSON, OF ATTLEBORO, MASSACHUSETTS, ASSIGNOR TO J. F. STURDY'S SONS CO., OF ATTLEBORO FALLS, MASSACHUSETTS, A CORPORATION OF MASSACHUSETTS.

BRACELET.

Application filed July 15, 1925. Serial No. 43,776.

To all whom it may concern:

Be it known that I, NELS T. NELSON, a citizen of the United States, residing at Attleboro, in the county of Bristol and State 5 of Massachusetts, have invented certain new and useful Improvements in Bracelets, of which the following is a specification.

This invention relates to an improved construction of extendible bracelet or chain structure, and has for its object to provide a bracelet of this character, which comprises a series of box-like units, each unit having two cooperating relatively-slidable band-shaped members, the body band member 10 having broad top and bottom walls and the connector band member having relatively narrow side walls for closing the sides of the body member, the latter member having an opening through which the end wall of the connector member may pass in connecting and disconnecting the links, a spring being provided for acting upon these link members to normally press them to contracted position.

25 A further object of this invention is to provide the body member with a transverse opening through its bottom wall adjacent the middle portion thereof, and to form the connecting band-shaped member so that one 30 of its end walls is adapted to pass through the space in the body link to connect and to disconnect one link from another.

A still further object of the invention is the provision of a guard or closure member 35 within the link members to close the slot when the links are contracted and to uncover the slot when the links are extended.

The invention further consists in the provision of an abutment portion formed on 40 this guard member to serve as a guide to assist in detaching the link members when in extended position.

A still further object of the invention is the provision of sliding guides on the connecting band link which also prevents the disengagement of the body and connecting link members unless they are tipped at an angle to each other.

With these and other objects in view, the 50 invention consists of certain novel features of construction, as will be more fully described, and particularly pointed out in the appended claims.

In the accompanying drawings:

Figure 1 is a side elevation illustrating a 55 portion of my improved link bracelet, its ends being provided with hooks whereby they are detachably connected to a wrist watch.

Figure 2 is a perspective view illustrating the body band member of the link folded to 60 provide broad top and bottom walls, the bottom wall being slotted transversely adjacent its middle portion.

Figure 3 is a perspective view of the connecting band member of the link folded 65 from sheet stock to close the sides of the body member.

Figure 4 is a perspective view of the guard or closure plate.

Figure 5 is a perspective view illustrating 70 the connector band as tipped up at an angle relative to the body band, whereby its end wall may be readily passed into and out of the body band through its slotted bottom wall.

Figure 6 is a central sectional side elevation showing the cover plate as closing the opening through the body band of one of the links, the link members being in contracted position.

Figure 7 is a central sectional bottom view of the parts illustrated in Figure 6.

Figure 8 is a sectional side elevation showing the link members in extended position with the closure plate in position to just permit the passage of the thin wall of the connector band through the slot of the body band.

Figure 9 is a bottom view of the parts in the position illustrated in Figure 8.

Figure 10 is a sectional view on line 10-10 of Figure 6.

It is found in the practical construction and operation of extendible bracelets of this character, of advantage to provide a series of box-shaped link units, each comprising two cooperating, relatively-slidable, band-shaped members, the body member having a broad or extended top wall to receive the maximum display or ornamentation and also provided with a broad under bearing surface or wall so as not to cut, abrade or injure the arm of the wearer when in engagement therewith. It is also found of advantage to provide a transverse opening through this bottom wall adjacent its middle 100 105

portion to permit the passage of the end wall of the connector band through this opening whereby the links may be readily connected to and disconnected from each other to permit insertion or removal of one or more links of the bracelet or chain to adjust its operating length; also to provide a closure plate to guard the opening through the body band and prevent accidental disengagement of the members when in partially expanded position; a spring being also provided to act upon the band members on each link unit to press them normally to contracted position; and the following is a detailed description of the present embodiment of my invention showing one means by which these advantageous results may be accomplished:—

With reference to the drawing, 10 designates the body or broad band link member, the same being preferably formed from a strip of sheet metal having a relatively broad upper plate or wall 11 adapted to receive the maximum amount of ornamentation on its outer surface, also a relatively broad bottom plate or wall 12 to provide an extended bearing surface for the link upon the arm of the wearer. This bottom plate is provided with a transverse slot 13 therethrough, preferably adjacent its middle portion to provide an opening for the entrance or exit of the end portion of the next adjacent connecting link member and the walls of this body band link are spaced apart by their end walls 14 and 15, the end wall 15 being notched as at 16 to receive the guides on the connecting links, as presently described.

Each of the connecting band links 17 is provided with opposite side walls 18 which have inwardly-extending elongated bearing enlargements or guides 19 to fit into and slide longitudinally between the top and bottom walls of the body band link and to enter the notches 16 in the end wall of the body link; also this connecting link is provided with a thin end wall 20 of no greater thickness than the side walls, which is reduced in height to slide between the walls of the body band 10, and the free ends of this connecting link are oppositely notched as at 21 to provide interengaging hook-shaped portions adapted to be snapped one into the other for the purpose of automatically connecting these free ends together when ready to be snapped into position in the body link and these hook-shaped portions may be soldered if desired for additional strength at this point.

By forming inwardly-extending guideways or bearing portions 19 on this connecting band link, it is nicely held in alignment with the body link and at the same time permits free sliding movement therein. Furthermore these portions 19 act to

prevent accidental disengagement of the links, for while the end wall 20 of the connecting band is thin enough to slip freely through the opening 13, the said portions 19, co-acting with the end wall 14 of the body link, prevent the end wall 20 coming into registration with the opening 13, unless the connecting band link is first tipped up at an angle relative to the body link.

In order to permit flexible contracting and expanding action of these bracelet links, I have mounted a coil spring 22 in each of the link units to act between one end of the body band and one end of the connecting band to normally press the links of each unit into contracted position and also permit an extending movement between them.

The links of my improved bracelet structure are substantially box-shape in construction having relatively broad top and bottom walls to respectively receive the maximum amount of ornamentation, to provide the maximum bearing surface against the flesh of the wearer, and to also close the bottom of the link; also the top and bottom walls of this band link are narrowly spaced apart, the space being sufficient to receive the operating spring between them, and the sides of these body band links are closed by the connecting links which slide along the sides thereof being normally held in closed or contracted position by action of the spring mounted therein.

Within the body band member, I have mounted a closure plate 23 which is provided on its sides with inwardly-turned wings 24 to hold the plate in lateral alignment and also form a stop to limit the expansion of the two members and also serve as an abutment to assure positive movement of the plate to uncover the slot, and I have provided an inturned end flange 25 which serves as a guiding abutment to assist in directing the link member outwardly through the slot 13 in the body member in detaching the same when the link members are in extended position. This closure plate is moved by frictional contact with the spring and the sliding parts to uncover the opening 13 through the body band when the parts are moved to extended position, and the final movement of the plate being positive by engagement of the link with the wings 24 which serve as an abutment to positively move the plate to uncover the slot permitting the passage of the end bar 20 of the connecting band therethrough. Also, when these parts are released the spring 22 acts to move the plate to closed position and this inturned end 25 is engaged by the bar 21 of the connector band and is forced into the position illustrated in Figures 6 and 7 in which position the body of this plate entirely closes the opening 13 to prevent the entrance of foreign matter.

By my improved construction the different links may be readily connected to and disconnected from each other to readily adjust the operating length of the bracelet, 5 while at the same time there is no possibility of accidental disconnection of the links.

The foregoing description is directed solely towards the construction illustrated, but I desire it to be understood that I reserve the privilege of resorting to all the 10 mechanical changes to which the device is susceptible, the invention being defined and limited only by the terms of the appended claims.

15 I claim:

1. An extendible bracelet structure comprising a series of box-shaped link units, each having two cooperating relatively slideable sheet metal band links, one forming 20 broad top and bottom walls and the other comparatively narrow side closing walls, the bottom wall of said band link having a lateral slot at substantially the middle of its length to permit the passage of a side band 25 link therethrough for ready detachment of the units one from the other.

2. In an expanding bracelet structure, a series of body band links formed of sheet stock folded to provide broad top and bottom walls, the latter wall having a transverse slot therethrough, and a relatively narrow connecting band link folded from sheet stock to form sliding side walls to normally close the side spaces of the body link, the end wall of a connector band link 30 being of such longitudinal width as to prevent free passage through said slot when the links are in extended position.

3. An extendible bracelet structure comprising a series of body band links formed of sheet stock folded to provide top, end and bottom walls with the ends of the band located in the bottom wall and spaced apart to provide a transverse slot, connecting side 45 band links slideable in said body links and forming closures for the sides thereof, the ends of each of said side band links being insertable and removable through one of said slots by manual manipulation.

4. In an expanding bracelet structure, a series of body band links folded from a strip of sheet stock to leave a space between its ends adjacent the middle portion of one of its walls, and a one-piece connector band link folded from sheet stock to slide in and form closing side walls for said body link, the end wall of a connector link being adapted to be passed through the space in the body link, a spring acting between the bands of each unit to hold them normally contracted, and a relatively movable member for 55 normally closing said space and also serving as a guide to assist in detaching the link members when in extended position.

5. An extendible bracelet structure comprising a series of box-shaped link units, each having two cooperating relatively slideable band links, one forming broad top and bottom walls and the other comparatively narrow side closing walls, the bottom 60

wall of said band link having a lateral slot at substantially the middle of its length to permit the passage of a band link therethrough, springs acting between said band links to normally hold them in contracted 70 position, and a cover plate movable with said side closing band link to close said slot when said links are in contracted position.

6. In an expanding bracelet structure, a series of body band links formed of sheet 75 stock folded to provide broad top and bottom walls, the latter wall having a transverse slot therethrough, and a relatively narrow connecting band link folded from sheet stock to form sliding side walls to 80 normally close the side spaces of the body link, the end wall of a connector band link being adapted to pass through said slot when the links are in extended position, springs for normally holding the links contracted, 85 and a closure plate slideable in said body link to close said slot when the links are contracted and to uncover the same when extended.

7. In an expanding bracelet structure, a series of body band links formed of sheet stock folded to provide broad top and bottom walls, the latter wall having a transverse slot therethrough, and a relatively narrow connecting band link folded from sheet stock to form sliding side walls to 90 normally close the side spaces of the body link, the end wall of a connector band link being adapted to pass through said slot when the links are in extended position, springs 95 for normally holding the links contracted, and a closure plate slideable in said body link to close said slot when the links are contracted, and to uncover the same when extended, said closure plate having an abutment portion to assist in guiding said end wall of the connector link outwardly through said slot.

8. In an expanding bracelet structure, a series of body band links folded from a strip 110 of sheet stock to leave a space between its ends adjacent the middle portion of one of its walls, and a one-piece connector band link folded from sheet stock to slide in and form closing side walls for said body link, the end wall of a connector link being adapted to be passed through the space in the body link, a spring acting between the bands of each unit to hold them normally contracted, and a relatively movable member for 115 normally closing said space and also serving as a guide to assist in detaching the link members when in extended position.

9. An extendible bracelet structure comprising a series of box-shaped link units, 120 each having two cooperating relatively slideable band links, one forming broad top and bottom walls and the other comparatively narrow side closing walls, the bottom walls of said band link having a lateral slot at 125

- substantially the middle of its length to permit the passage of a side band link therethrough, springs in each unit to act between said band link to normally hold them in contracted position, a closure plate for said slot slidable relatively thereto, and side ears on said plate between the walls of said side band link to guide the plate in its sliding actions.
- 5 10. An extendible bracelet structure comprising a series of body band links having broad top and bottom walls, connecting band links having side closing walls with inwardly extending guides for slidably engaging said top and bottom walls of said body link, said bottom wall having a transverse slot at substantially its middle portion, the ends of said guides being spaced from the ends of said connecting band links and forming 15 abutments to prevent the end wall of said
- 20

connecting band from being moved into registration with said slot until said links are tipped at an angle to each other.

11. An extendible bracelet structure comprising a series of body band links having 25 top, bottom and end walls, one of said end walls being slotted, said bottom wall being provided with a transverse slot, connecting band links having side closing walls inwardly extending guideways in said connecting 30 links slidably engaging said top and bottom and notched walls and spaced from one end of said connecting link to provide an abutment to prevent the unnotched wall of said body band registering with said slot unless 35 the connecting links are tipped at an angle to the body link.

In testimony whereof I affix my signature.

NELS T. NELSON.
